CART FOR OXYGEN CYLINDERS

John P. Salsgiver, 29 Ethan Allen Drive,
Acton, Mass. 01720

Filed June 22, 1973, Ser. No. 372,831

Term of patent 14 years

Int. Cl. D12—02

U.S. Cl. D12—29

FIG. 1

FIG. 2

FIG. 3

FIG. 1 is a perspective view of a cart for oxygen cylinders showing my new design.

FIG. 2 is a typical end elevational view; and

FIG. 3 is a typical side elevational view thereof.

I claim:

The ornamental design for a cart for oxygen cylinders, as shown.
